(57) **CLAIM**

I claim the ornamental design for a pet toy, as shown and described.

DESCRIPTION

FIG. 1 is a perspective view of a pet toy showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof; and,

FIG. 9 is an exploded view of FIG. 1.

The broken lines in the drawings depict portions of the pet toy that form no part of the claimed design.

1 Claim, 9 Drawing Sheets
